Primary Examiner — T. Chase Nelson*Assistant Examiner* — Michelle E Wilson(74) *Attorney, Agent, or Firm* — Knobbe, Martens, Olson & Bear LLP**CLAIM**

The ornamental design for an organ protection layer, as shown and described.

DESCRIPTION

FIG. 1 is a perspective view of an embodiment of an organ protection layer.

FIG. 2 is a top plan view of the organ protection layer of FIG. 1.

FIG. 3 is a bottom plan view of the organ protection layer of FIG. 1.

FIG. 4 is a right or left side elevation view of the organ protection layer of FIG. 1; and,

FIG. 5 is a front or rear elevation view of the organ protection layer of FIG. 1.

The dashed or broken lines on the organ protection layer form a part of the claimed design.
